C. E. COE.
AERIAL PROJECTILE TOY.
APPLICATION FILED DEC. 6, 1910.

991,138.

Patented May 2, 1911.

UNITED STATES PATENT OFFICE.

CHARLES E. COE, OF ST. LOUIS, MISSOURI, ASSIGNOR OF ONE-HALF TO EDWARD B. BICKER, OF ST. LOUIS, MISSOURI.

AERIAL PROJECTILE TOY.

991,138.

Specification of Letters Patent.

Patented May 2, 1911.

Application filed December 5, 1910. Serial No. 595,693.

To all whom it may concern:

Be it known that I, CHARLES E. COE, a citizen of the United States, and resident of St. Louis, Missouri, have invented certain new and useful Improvements in Aerial Projectile Toys, of which the following is a specification containing a full, clear, and exact description, reference being had to the accompanying drawings, forming a part hereof.

My invention relates to improvements in aerial projectile toys, the object of my invention being to construct a toy, one member of which is a projectile adapted to be discharged into the air, having blades acting upon the air to give the projectile a whirling motion, one pair of diametrically, opposite blades being of unequal areas, thereby when the projectile is discharged the pair of unequally sized blades will cause the projectile to describe a substantially spiral course through the air.

A further object of my invention is to construct such a projectile from a single piece of metal and to form integrally with the ends of the blades and from the same piece of metal a reinforcing and protecting rim. And a further object of the invention is to construct a simple means for projecting the projectile, which means comprises a rectangular, reinforced opening centrally disposed of the projectile and a rod, rectangular in cross section and twisted so that it is provided throughout its length with a number of helices of a given pitch and from this point to its outer end the helices gradually increase in pitch as required to facilitate the operation of projecting.

With the above purposes in view my invention consists in certain novel features of construction and arrangement of parts as will be hereinafter more fully described, pointed out in the claims and illustrated by the accompanying drawings, in which—

Figure 1 is a detail, sectional elevation of the complete toy; Fig. 2 is a sectional plan taken on the line 2—2 of Fig. 1; Fig. 3 is a plan of the projectile, the rod of the projector being shown in section; Fig. 4 is an edge view of the projectile a portion of which is in section as indicated by the line 4—4 of Fig. 3; Fig. 5 is a fragmental portion of the projectile showing the initial incision necessary to form the reinforced opening in the projectile; Figs. 6 and 7 show

the second step in the formation of the reinforced opening, the spurs formed by the V-shape incision being struck downwardly; Figs. 8 and 9 illustrate the completed reinforced opening; and Fig. 10 illustrates in section a portion of the projectile surrounding the rod of the projector.

Referring by numerals to the accompanying drawings: 1 designates the body portion of the projector which, as shown, is formed from a single piece of flat wire which is rectangular in cross section. At the lowermost end the rod is bent to form a loop handle portion 2 and the entire rod, except for said handle is twisted helically, the helices for a certain length of the rod being of a uniform pitch and from this on to the upper end of the rod the pitch of the helices gradually increases for purposes hereinafter made clear. Loosely embracing and arranged for movement lengthwise of the rod is a sleeve 3, at the central portion of which there is preferably provided an enlarged, annular rib 4, or gripping ring.

The projectile is constructed preferably from a single piece of sheet metal and, as shown, is preferably formed in the shape of a bird having out-stretched wings, which wings are designated by the reference character 5, a head 6, a tail 7 and a body portion 8.

The wings 5, the head and tail 6 and 7 are deflected from the plane of the body 8 in the manner of ordinary propeller blades and the tail 7 is preferably made of greater area than the head 6 for purposes hereinafter made clear. Connecting the head, wings and tail is an integral, reinforcing and protecting annular rim 9.

Centrally disposed in the body portion 8 is a rectangular opening 10, the margins of which are reinforced by V-shape spurs 11 which are struck from the body portion 8 and folded backwardly against the body portion.

The projectile just described is of such nature that it may be readily stamped and formed by a single operation of the machine, which machine is provided with cutting dies arranged slightly in advance of "formers" 105 so that after the material is cut a further movement deflects the blades of the projectile, namely the head, wings and tail, moves the V-shape spurs, for reinforcing the central opening, to a right angled position rela-

tive the body 8 and turns the rim 9 to a position at right angles to the sheet from which it was formed, the final finishing of the spurs for reinforcing the opening 10 may 5 be either done by hand or a second operation of the same or another machine.

Assuming now that the parts be assembled, as shown in Fig. 1, and it be desired to operate the toy the operator grasps the handle 10 2 in his left hand and moves the sleeve 3 with his right hand upwardly over the twisted rod 1 carrying with the sleeve the projectile which, by reason of the twist in the rod and the rectangular opening in the 15 projectile, is given a rotary movement and, for the reason that at the lowermost end of the rod 1 the pitch of the twists or helices is very slow, a minimum of effort is required to start the projectile and, for the 20 reason that the pitch is, from this on to the end of the rod, gradually increased, there may be imparted to the projectile a rapidly increasing rotary motion with a decreasing longitudinal movement of the operating 25 sleeve 3.

After the projectile leaves the starting rod 1 it will, by reason of the shape of the head, wings and tail, which are likened unto the blades of a propeller, soar or fly in the 30 air and, for the reason that one of the blades, namely the tail, is of greater area than the blade, namely the head, opposite it thereby offering a greater area and resistance to the air, the projectile as a whole will not only 35 describe a rotary motion on its own axis but will be moved in a spiral course.

By the provision of the reinforcing and protecting rim 9 the blades are protected 40 against breakage by contacting with objects in the course of its flight and the object struck by the projectile is not subjected to the sharp cutting edges of the blades.

I am aware that a bladed projectile, adapted to be discharged over a twisted rod, 45 is not broadly new.

I claim:

1. A projectile, comprising a body portion shaped to conform with the outline of a bird having out-stretched wings, the head, wings and tail of the bird being propeller 50 blades, one of which has a greater area than the remaining blades, and there being a non-circular opening in the body portion of the projectile.

2. A projectile, comprising a body portion 55 shaped to conform with the outline of a bird having out-stretched wings, the head, wings and tail of the bird being propeller blades, one of which has a greater area than the remaining blades, there being a non-circular 60 opening in the body portion of the projectile, and a rim inclosing said blades.

3. An aerial projectile apparatus, comprising in combination a bladed projectile having a non-circular opening in its body 65 portion, and a projector being non-circular in cross section and formed helically, the helices varying in pitch throughout the length of the projector.

4. An aerial projectile apparatus, comprising in combination a bladed projectile having a non-circular opening in its body portion, a projector being non-circular in cross section and formed helically, the helices varying in pitch through the length of the 75 projector, and a sleeve arranged to be moved freely over the projectile, for the purposes stated.

5. In an apparatus of the class described, a projector formed from a single piece of 80 material non-circular in cross section and helically formed, the helices varying in pitch throughout the length of the projector.

In testimony whereof, I have signed my 85 name to this specification, in presence of two subscribing witnesses.

CHARLES E. COE.

Witnesses:

EDWARD E. LONGAN,
E. L. WALLACE.
